CLAIM

The ornamental design for a bench seat for a vehicle, as shown and described.

DESCRIPTION

FIG. 1 is a front right perspective view of a bench seat for a vehicle according to the present invention.

FIG. 2 is a front left perspective view of the bench seat for a vehicle shown in FIG. 1.

FIG. 3 is a rear left perspective view thereof.

FIG. 4 is a rear right perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof.

FIG. 10 is a front right perspective view of a bench seat for a vehicle according to a second embodiment of the present invention.

FIG. 11 is a front left perspective view of the bench seat for a vehicle shown in FIG. 10.

FIG. 12 is a rear left perspective view thereof.

FIG. 13 is a rear right perspective view thereof.

FIG. 14 is a front view thereof.

FIG. 15 is a rear view thereof.

FIG. 16 is a left side view thereof.

FIG. 17 is a right side view thereof.

FIG. 18 is a top view thereof.

FIG. 19 is a front right perspective view of a bench seat for a vehicle according to a third embodiment of the present invention.

FIG. 20 is a front left perspective view of the bench seat for a vehicle shown in FIG. 19.

FIG. 21 is a rear left perspective view thereof.

FIG. 22 is a rear right perspective view thereof.

FIG. 23 is a front view thereof.

FIG. 24 is a rear view thereof.

FIG. 25 is a left side view thereof.

FIG. 26 is a right side view thereof; and,

FIG. 27 is a top view thereof.
